COMBINED WATER AND FERTILIZER APPLICATOR

Joseph Cefalde, 29 Millet Ave., Youngstown, Ohio

Filed Sept. 20, 1965, Ser. No. 87,075

Term of patent 14 years

(Cl. D35—1)

FIGURE 1 is a perspective view of a combined water and fertilizer applicator, showing my new design;

FIGURE 2 is a perspective view showing the bottom, top and one side thereof;

FIGURE 3 is a perspective view of a modification of the Combined Plant Support and Water Applicator showing my new invention;

FIGURE 4 is a perspective view showing the bottom, top and one side of the modification of FIGURE 3.

This is a continuation-in-part of design applications Serial Nos. D83,639 and D86,704, filed February 1, 1965, and August 25, 1965, respectively, and now abandoned.

I claim:

The ornamental design for a combined water and fertilizer applicator, as shown and described.
